United States Patent Office.

SAMUEL G. CABELL, OF QUINCY, ILLINOIS.

Letters Patent No. 73,872, dated January 28, 1868

IMPROVEMENT IN PREVENTING INCRUSTATION OF STEAM-BOILERS.

The Schedule referred to in these Letters Patent and making part of the same.

TO ALL WHOM IT MAY CONCERN:

Be it known that I, SAMUEL G. CABELL, of Quincy, in the county of Adams, and State of Illinois, have invented a new and useful Improvement in Apparatus for Preventing the Formation of Scale in Boilers, and removing such incrustation as may have been already formed at the time of its application; and I do hereby declare that the following is a full, clear, and exact description of the same, reference being had to the accompanying drawings, forming part of this specification, in which—

Figure 1 is an elevation, partly in section, of the apparatus, as constructed and arranged.

Figure 2 is an elevation, partly in section, of a multiplied or compound magnet detached, to be applied as shown at F in fig. 1.

Figure 3 is a horizontal section on the line x x on fig. 1.

Figure 4 is a similar section on the line y y.

Figure 5 is a similar section on the line z z; and

Figure 6 is an elevation of the upper portion of the battery used in connection with the magnet shown in fig. 2.

Figure 7 is a sectional view, showing the method of attaching the plate G to the magnet L.

The same letters are employed in all the figures in the indication of identical parts.

The object of this invention is to generate electric currents for the purpose set forth in the title hereof; and it consists in the application of an electro-magnet, provided with a number of points within a chamber connecting with the steam-chamber of the boiler by means of a pipe, having a stop-cock by which to cut off or regulate its action, the helix of said magnet being connected with the poles of an electric battery.

The following description will enable one skilled in the art to make and use my apparatus.

A represents part of the shell of a cylindrical boiler, to which is attached the pipe B, provided with a stop-cock, B'. This pipe may be constructed with flanges, as shown in fig. 1, by which the cylindrical chamber C may be attached to it. On the upper end of this chamber is bolted the stuffing-box D, with its follower E. The magnet F, fig. 1, constructed as hereinafter described, passes through the stuffing-box D, where it is surrounded and insulated by gutta percha or other suitable non-conductor, and in the collar E, and lower part of the stuffing-box, it is sustained by strips of gutta percha, or other suitable insulators, arranged as shown in fig. 5, the packing in the stuffing-box being steam-tight, as well as a non-conductor. About midway of the packing in the stuffing-box, the magnet is provided with a collar secured to it, which, being firmly clamped by the packing, prevents the steam from forcing up said magnet. This may also be accomplished by other means, which it is not necessary to describe here. On the lower end of the magnet F is fastened, by means of a collar on its upper side, fitting closely around said magnet, as shown in fig. 7, and suspended within (and not in contact with) the chamber C, the plate G, from the lower face of which the pointed pins G' project. These points are of soft iron or other suitable material, gold-plated, and tipped with platinum, and being connected by means of the plate G, of the same material, with the magnet F or L, become magnetic whenever the electric circuit is closed.

The tube L is rendered magnetic and constructed as follows: An iron pipe constitutes the external shell, and into this is inserted the central core L', which is surrounded by a copper wire, insulated by being coated with gutta percha or other suitable material. This wire is coiled around the core L', from top to bottom and from bottom to top, so that the insulated wire is carried twice in coils, or oftener if deemed necessary, along the entire length of the core, and within the external shell. The ends of the wire M are then connected with the two poles of an electric or galvanic battery, O, and the pipe and central core become magnetic by the action of the electric or galvanic current.

When this apparatus is in use, the ground-connection is made by passing a wire through the hole a in the upper pointed tip I. The other end of said wire, communicating with the ground, establishes the current, by which means the electricity received by the points G' is conveyed off and discharged from the boiler.

Having thus described my invention, what I claim as new, and desire to secure by Letters Patent, is—

1. The multiplied or compound electro-magnet L, constructed substantially as described, and arranged in combination with the chamber C, points G, and battery O, essentially as described.

2. The application of the electro-magnet within a steam-boiler or chamber connected therewith, to prevent incrustation, substantially as specified.

S. G. CABELL.
